UNITED STATES PATENT OFFICE.

DAVID H. HILL, OF PHILADELPHIA, PENNSYLVANIA.

CIRCULAR-KNITTING MACHINE.

SPECIFICATION forming part of Letters Patent No. 393,010, dated November 20, 1888.

Application filed September 15, 1887. Serial No. 249,753. (No model.)

To all whom it may concern:

Be it known that I, DAVID H. HILL, a citizen of the United States, residing in the city and county of Philadelphia, State of Pennsylvania, have invented a new and useful Improvement 5 in Circular-Knitting Machines, which improvement is fully set forth in the following specification and accompanying drawings.

My invention consists in dampening and 10 tension regulating device for the yarn or thread supplied to a knitting-machine constructed as herein described and claimed.

Figure 1 represents a front elevation of a 15 knitting-machine embodying my invention. Fig. 2 represents a side elevation thereof, partly sectional in line *xx*, Fig. 1.

Similar letters of reference indicate corresponding parts in the several figures.

Referring to the drawings, A represents a 20 knitting-machine, which, excepting the features of my invention applied thereto, is of usual construction.

B represents the driving-shaft of the 25 machine, on which is feathered the bevel-wheel C, which may be engaged with and disengaged from the bevel-wheel D of the cylinder of the machine, so that the machine may be started and stopped. The shaft B also carries a clutch, E, one wheel or pulley, E', whereof is feathered 30 on said shaft and the other wheel or pulley, E'', is loose thereon.

F represents a lever which is pivoted to the 35 frame of the machine and to an arm, G, the ends of which carry shippers H J, respectively. The shipper H engages with the groove or neck *a* of the hub of the wheel C, and the shipper J engages with the groove or neck *b* of the wheel E'.

It will be seen that when the lever F is operated 40 in one direction the wheel C is caused to mesh with the wheel D, whereby the machine is started. The pulley E' is also clutched with the pulley E'', and thus the latter is rotated simultaneously with the starting of the machine A. It is evident that by moving the 45 lever F in the opposite direction the machine will be stopped and the clutch separated, whereby the pulley E'' is at rest.

K represents a frame which rises from the 50 frame of the machine, and supports at its upper end a trough or pan, L, and also a cylin-

der, M, which dips into said trough. Secured to the journal of the cylinder M is a pulley, N, around which passes an endless belt, P, which also passes around the clutch-pulley E'' 55 and guide-pulleys Q, the latter being mounted on the frame K intermediate of the pulleys N E'.

Meshing with the gear-wheel R on the cylinder of the machine is a pinion, S, which is 60 secured to a vertical shaft, T, the latter being mounted on the frame of the machine and carrying at its upper end a guide and tension roller, U, adjacent to which is an eye or guide, V, it being noticed that the yarn supplied to 65 the machine passes over or around the cylinder M, then through the eye V, and next around the roller U, from whence it is directed to the needles.

The trough or pan L contains grease, oiling, 70 or other material for dampening the yarn, so that as the yarn is brought into contact with the cylinder M the yarn is dampened, in which condition it is supplied to the needles. When the machine is started, the roller U and cylinder M simultaneously rotate, and the yarn is drawn by said roller and dampened by said cylinder. When the machine is stopped by operation of the clutch E, through the medium 75 of the lever F, the roller U and cylinder M cease their rotation, and thus the advance of the yarn and dampening of the same discontinue.

Having thus described my invention, what I 80 claim as new, and desire to secure by Letters 85 Patent, is—

1. A dampening device for the yarn of a knitting-machine, consisting of a cylinder or roller and a trough, a pulley on said roller, a driving-shaft with clutch mechanism thereon, 90 the latter consisting of a fast and a loose pulley, a band on said roller-pulley and on the loose pulley of the clutch mechanism, and a shifting device for said clutch mechanism, said parts being combined substantially as described.

2. The combination of the cylinder M, having the pulley N on its journal, with the trough L below said cylinder, the driving-shaft B, with grooved bevel-wheel C, loose clutch-pulley E'' 100 and fast clutch-pulley E' thereon, the band B on said pulley N and on said loose clutch-pul-

ley, mechanism, substantially as described, for shifting said fast clutch-pulley and said grooved bevel-wheel, and a needle-cylinder having a bevel-wheel, D, connected therewith 5 and gearing with the bevel-wheel C, substantially as and for the purpose set forth.

3. The combination of the driving-shaft B, with the grooved bevel-wheel C thereon, a clutch mechanism consisting of a fast and a 10 loose pulley on said driving-shaft, a dampening-cylinder and a trough, a pulley on said cylinder, a band on said cylinder-pulley and said loose clutch-pulley, a lever pivoted to the frame of the machine, an arm attached to said 15 lever and provided with shippers adapted to operate said grooved bevel-wheel and said fast clutch-pulley, and a needle-cylinder having a bevel-wheel gearing with said grooved bevel-

wheel, substantially as and for the purpose set forth.

4. A dampening and tension device for the 20 yarn supplied to a knitting-machine, consisting of a cylinder suitably journaled in an attachment to the frame of the machine, a trough located below said cylinder and into which the 25 cylinder dips, a vertical shaft mounted on the frame of the machine, mechanism, substantially as described, for rotating said shaft, a roller on said shaft, and an eye or guide adjacent to said roller, said parts being combined and operated substantially as described.

DAVID H. HILL.
